UNITED STATES PATENT OFFICE.

CHARLES A. BAILEY, OF MIDDLETOWN, CONNECTICUT.

TOY.

SPECIFICATION forming part of Letters Patent No. 315,380, dated April 7, 1885.

Application filed August 16, 1884. (No model.)

To all whom it may concern:

Be it known that I, CHARLES A. BAILEY, a citizen of the United States, residing at Middletown, in the county of Middlesex and State of Connecticut, have invented certain new and useful Improvements in Swinging Toys; and I do declare the following to be a full, clear, and exact description of the invention, such as will enable others skilled in the art to which it applies to make and use the same, reference being had to the accompanying drawing, and to letters or figures of reference marked thereon, which form a part of this specification.

The figure of the drawing is a perspective view of my device.

This invention has relation to automatic swinging toys; and it consists in the construction and novel arrangement of devices, as hereinafter set forth, and pointed out in the appended claim.

In the accompanying drawing, the letter A designates the body of the toy, which is preferably made in skeleton form, and is perforated at B B for the passage of the axles C and D, to which the wheels E are attached. To the middle portion of the body A is pivoted a lever, F, which extends upward, and is laterally bent, so that its slotted arm G will vibrate on one side of the center when the lever is in motion. The lower short arm, H, of the lever is connected to the crank L of the axle by a rod,

K, so that when the carriage is in motion the slotted lever will be set in action. From the body portion A extends upward over the middle thereof a wire rod or support, S, to which is pivoted a swing, Z, which is constructed with a lateral projection, m, adapted to be engaged by the slot v of the vibratory arm G. The seat a of the swing is usually perforated at b b for the passage of a cord, so that a small doll or other article may be tied in connection therewith.

When the toy is drawn along, the revolution of the crank-axle causes the lever to vibrate back and forth, producing a lively motion of the swing.

Having described this invention, what I claim, and desire to secure by Letters Patent, is—

A swinging toy consisting of a carriage having a crank-axle, a vibratory lever having a laterally-bent slotted arm, a link connecting the vibratory lever with the crank-axle, and a swing suspended above the carriage and having a lateral projection engaging the slot of the lever-arm, substantially as specified.

In testimony whereof I affix my signature in presence of two witnesses.

CHAS. A. BAILEY.
